(57) **CLAIM**

We claim the ornamental design for a control device, as shown and described.

DESCRIPTION

FIG. 1 is a top, front, left perspective view of an embodiment of the claimed design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top, front, left perspective view of an embodiment of the claimed design;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a top, front, left perspective view of an embodiment of the claimed design;

FIG. 16 is a front view thereof;

FIG. 17 is a rear view thereof;

FIG. 18 is a right side view thereof;

FIG. 19 is a left side view thereof;

FIG. 20 is a top view thereof; and,

FIG. 21 is a bottom view thereof.

The broken lines in the drawing views show portions of the control device that forms no part of the claimed design. The control device is shown broken away in FIGS. 8-21 views of the drawing to indicate indeterminate length, it being understood that it has a uniform shape and appearance throughout its length.

The control device include, but is not limited to, thermostats, defrost controls, sensors, and other heating, ventilation, air-conditioning, and refrigeration equipment controls.
